UNITED STATES PATENT OFFICE

SYLVANUS A. REED, OF NEW YORK, N. Y., ASSIGNOR TO THE REED PROPELLER CO., INC.,
OF NEW YORK, N. Y., A CORPORATION OF NEW YORK

TANDEM AERONAUTICAL PROPELLER

Application filed December 22, 1928. Serial No. 327,764.

My invention relates to tandem aeronautical propellers.

In my U. S. Patents #1,463,556 and #1,518,410, granted August 31, 1923 and December 9, 1924, respectively, propellers having solid blades formed of forged light strong alloys are described and illustrated. It is stated in said patents that such propellers may be run efficiently at higher speeds than heretofore, and that the blades thereof may be made in a single piece from an elongated flat rolled plate of metal, such as duralumin, twisted at the center to establish the maximum pitch angles at the blade roots, and then 10 twisted (each blade) in the reverse direction progressively to the tip to establish the pitch angles appropriate for the different radii. Where a four blade propeller, a six blade propeller, and so on, is required, it is further suggested, in said patents, that two or more 20 such propellers be mounted on a single hub and that the hub structure be appropriately modified to receive them. Nowhere, however, in said issued patents, is there any definite teaching as to the manner in which the 25 tandem blade idea may best be carried out. The present invention, as distinguished from the broad suggestions contained in said patents, relates specifically to a developed means whereby the tandem blade idea as applied to 30 aeronautical propellers may be put to practical use. Not only are the spacing limits of the parallel or tandem blades clearly defined, but in addition, that blade form and that 35 blade angle best suited to a practical tandem or biplane blade aeronautical propeller clearly set forth. Also, as a mounting for said tandem blades, an improved and practical form of propeller hub structure is described 40 and illustrated.

The hub, in its preferred embodiment, comprises a tubular member internally keyed or splined to receive the engine shaft, a central flange formed upon said tubular member intermediate of its ends, spacer members (preferably elongated filler blocks) between each face of said flange and the respective opposed faces of the propellers, and bolts passing thru both propellers, both filler blocks and said 45 flange, the holes for said bolts being disposed

preferably in the long axis of the propeller and at a substantial radius out from said tubular member to minimize torque stresses. Preferably the tandem blades, at their outer ends, and throughout a material portion of 55 their respective lengths, have a depth of chord less than the depth of the gap between said blades, whereas the pitch angles and depth of chord of said blades, at an intermediate point, is such that the leading edge of 60 the rear blade overlaps or extends forwardly beyond the trailing edge of the forward blade notwithstanding the fact that said blades, from end to end, are preferably substantially 65 parallel.

The advantages of a tandem aeronautical propeller thus characterized will appear from the detail description hereinafter given.

In the drawings, wherein like reference characters denote like or corresponding 70 parts,

Fig. 1 is a plan view of the metal hub about which my improved propeller may be assembled;

Fig. 2 is a section on the line 2—2 of 75 Fig. 1;

Fig. 3 is a plan view of a spacer member used in assembling my improved propeller;

Fig. 4 is an elevation of the spacer member shown in Fig. 3;

Fig. 5 is a plan view of my improved tandem propeller assembled;

Fig. 6 is a cross section on the center line of the propeller;

Fig. 7 is a cross section on the line 7—7 of 85 Fig. 5; and

Fig. 8 is an elevation of one of the propellers of the assembled propeller, one of the filler blocks being likewise shown in elevation, whereas the tubular member or hub 90 sleeve and the bolts are shown in section.

In Fig. 1 there is shown the metal hub (preferably steel) with the tubular part 1 and elongated flange 2 formed thereon intermediate of its ends.

In Fig. 2 the flange 2 is shown in plan and the tubular portion 1 in section. 3 is a keyway formed in said tubular member and 95 5—5 are bolt holes formed in said flange 2 near its outer ends.

The spacer members or hub blocks are preferably formed of cast aluminum alloy. 6—6 are bolt holes formed in said blocks to coincide with the bolt holes 5—5 formed in 5 the hub flange; 7 is a central hole, somewhat larger than the tubular member 1 to receive it; and 8—8 are lightening holes formed in said blocks intermediately of the central hole 7 and the bolt holes 6—6.

- 10 The assembled tandem propeller is made up of propellers 9 and 10, which are fabricated preferably from forged aluminum alloy, somewhat flat in the central part, and twisted in that part to establish the maximum 15 pitch angles at the blade roots, the blades being reversely twisted progressively from the blade roots out toward the blade tips to establish throughout such portion of the blade length the required pitch. Each propeller 20 has a central hole (undesignated) formed therein and the propeller 9 is mounted with the hub sleeve or tubular member 1 engaging in said hole at the forward side of the hub flange 2. The propeller 10 is similarly 25 mounted on the rear side of said flange and the spacer members or hub blocks 11 are interposed, one between the propeller 9 and the hub flange 2, and the other between the propeller 10 and the hub flange 2.

- 30 In Fig. 7 one of the bolts 4 for fastening the propeller to the hub is clearly shown.

In Figs. 5, 7, and 8, the bolts 4—4 are clearly indicated. Said bolts pass thru both propellers, both spacer members, and the hub flange, and are secured by nuts 12. 13—13 are bevelled bushings and/or washers shaped to the diagonal face of the propellers. If desired, instead of the propellers 9 and 10 being placed in exact parallelism, a slight stagger 35 may be given them, in which event the hub flange and hub blocks will be modified slightly as to form. I may also have three or more 40 filler blocks and more than one hub flange if and when three or more propellers, in tandem, are used.

As previously stated, the tandem blades are preferably uniformly spaced, altho in that embodiment of the invention deemed most practical under existing conditions, and 50 the spacing between blades is preferably such that throughout a portion of the blade lengths in the vicinity of the blade tips, such spacing or gap exceeds the length or depth of the blade chords (i. e. the distance from 55 the leading edge to the trailing edge of said blade). Moreover, as illustrated in Fig. 5, the blade angle and the depth of chord is preferably such that throughout a portion of the length of the tandem blades the rear propeller 10, along its leading edge, overlaps or 60 extends forwardly beyond the trailing edge of the forward propeller 9.

While I have described my invention in detail in its present preferred embodiment, 65 it will be obvious to those skilled in the art

after understanding my invention, that various changes and modifications may be made therein without departing from the spirit or scope thereof. I aim in the appended claims to cover all such modifications and changes. 70

What I claim is:

1. In an aeronautical propeller, a hub, and tandem blades extending out from said hub in uniformly spaced relation, said tandem blades from the inner third of their respective 75 lengths outwardly, having a gradually decreasing depth of chord which, throughout a material portion of the blade lengths in the vicinity of their tips, is less in depth than the depth of the gap between said tandem 80 blades.

2. In an aeronautical propeller, a metal hub including a substantially cylindrical hub sleeve having formed thereon, intermediately of its ends, an outwardly directed flange, 85 tandem blades extending out from said sleeve, one each, on opposite faces of said flange, and spacer members interposed between said flange and each said propeller blade.

3. In an aeronautical propeller, a metal 90 hub including a hub sleeve having formed thereon, intermediately of its ends, an outwardly directed flange, opposed tandem blades extending out from said hub sleeve, one each on opposite faces of said flange, the 95 corresponding blades of said opposed tandem blade groups being united integrally and the propellers formed, in each instance, from a single length of metal, and each said metal length having formed therein an opening 100 thru which said sleeve extends, and means penetrating each blade group and said flange for fastening the propeller to the hub.

4. In an aeronautical propeller, a metal hub including a hub sleeve having formed 105 thereon, intermediately of its ends, an outwardly directed flange, tandem integral propellers having blades extending out from said hub sleeve, one each on opposite faces of said flange, and means engaging said flange 110 and common to the tandem propellers of each group for fastening said propellers to the hub.

5. In an aeronautical propeller, a hub including a hub sleeve and an outwardly directed flange, tandem propellers having 115 blades extending out from said hub sleeve, one propeller each at opposite sides of said flange, spacer members interposed between 120 said flange and each said blade, and means spaced outwardly from said sleeve but within the radius of said flange for fastening said tandem propellers to said hub.

6. In an aeronautical propeller, a hub including a hub sleeve and carried thereby an elongated outwardly extending filler structure, and unit propellers each having formed 125 therein an opening to receive the hub sleeve, said propellers being disposed respectively on 130

opposite faces of the filler structure where they are fastened.

7. In an aeronautical propeller, a hub elongated in the direction of the long axis of the propeller, said hub having formed therein a central bore, and tandem propellers fastened to said hub, one each against the opposite faces thereof, the fastening means for each said propeller being extended thru said hub and thru said propellers at or near the outer ends of said elongated hub.

8. In an aeronautical propeller in which a plurality of tandem propellers each having a plurality of blades are positioned to rotate with a drive shaft about the axis of said drive shaft, a hub having an elongated flange extending along the longitudinal axes of the propeller blades and a plurality of elongated spacer elements positioned on opposite sides of the said flange, each of the said spacer elements having a substantially flat side abutting against the flange and having a curved surface shaped to conform substantially to the contour of one of the propeller blades and against which the said propeller blade bears.

In testimony whereof I hereunto affix my signature.
